United States Patent Office.

HENRY H. DICKINSON, OF WEST NORTHFIELD, MASSACHUSETTS.

Letters Patent No. 78,936, dated June 16, 1868.

IMPROVEMENT IN TAIL-CLASPS FOR MILKERS.

The Schedule referred to in these Letters Patent and making part of the same.

TO ALL WHOM IT MAY CONCERN:

Be it known that I, HENRY H. DICKINSON, of West Northfield, in the county of Franklin, and State of Massachusetts, have invented a new and useful Tail-Clasp for Milkers' Use; and I do hereby declare that the following is a full, clear, and exact description thereof, reference being had to the annexed drawings, making a part of this specification, and to the letters of reference marked thereon, in which—

Figure 1 is a perspective view of my invention, and

Figure 2 shows its application to use.

The nature of my invention consists in the construction of a clasp or spring, which is to be attached to the leg of a cow while being milked, said clasp being so constructed that the tail of the cow may be firmly grasped and held therein during the operation of milking.

Much annoyance is often experienced while milking, from the frequent whisking of the cow's tail in the face of the milker, especially during the summer, when flies are plenty, and various means have been resorted to to secure the cow's tail in some way, such as tying the tail to the leg, either by a string, or by the long hairs of the tail, but as yet no satisfactory, convenient, and quick method has been found.

My invention is designed to accomplish this purpose perfectly, and serves to render the operation of milking comparatively pleasant and agreeable.

That others may be able to make and use my invention, I will proceed to describe its construction and mode of operation.

A piece of metal, steel being preferable, of a convenient width and thickness, is heated, and bent into the form shown in fig. 1, A being a large loop, of sufficient size to encircle the leg of the cow, the extreme end of the metal forming said loop A being bent into a smaller loop, *a b*, said small loop pressing slightly against or coming very near to the part *c* of the clasp.

Another small loop is formed at *f*, the two parts *i i'* of the clasp, coming very near to or pressing against each other, the extreme end of the part *i'* being also bent into a small loop, *e d*. Instead of the loops *a b* and *e d* being formed at the two extreme ends of the piece of metal, a small button might be inserted in or attached to each end, or the end might be bent slightly, the object of said loops being merely for convenience, to be used as handles in opening the clasp.

After the metal is bent into the form shown in fig. 1, it is then tempered properly, so that when either loop *a b* or *e d* is pulled away from the part *c* and released again, the said loops may spring back to their original position, quite near to or against the part *c*.

Its application to use and its operation are as follows:

When the cow is to be milked, the loop *a b* is seized and pulled away from the part *c*. This opens the large part *A* of the clasp sufficiently to permit it to be slipped on to the cow's hind leg, just above the joint, as shown, and when said large loop *A* encloses or encircles the leg, the small loop *a b* is released, and springs back to its place against the part *c*, or against the leg of the cow. The other loop, *e d*, is then seized, and pulled in the opposite direction, and away from the part *c* of the clasp, the cow's tail placed either between the parts *i* and *i'*, or in the loop *f*, or in both, and the small loop *e d* being released, springs back against the part *c*, thus clasping the cow's tail firmly between the parts *i* and *i'*.

This instrument is cheap, easy of adjustment, perfectly sure in its operation, and does not hurt the cow, particularly if the long hairs of the tail be placed in the clasp.

Having thus described my invention, what I claim as new, and desire to secure by Letters Patent, is—

A tail-clasp, for milkers' use, when constructed and operating substantially as herein described and for the purposes specified.

HENRY H. DICKINSON.
